LAWN SPRINKLER

George L. Turner, Hickory Corners, Mich., assignor to
H. B. Sherman Manufacturing Company, Battle Creek,
Mich., a corporation of Michigan

Filed Oct. 5, 1962, Ser. No. 71,995

Term of patent 14 years

(Cl. D91—1)

FIGURE 1 is a top view of a lawn sprinkler, showing my new design.

FIGURE 2 is a side elevation thereof with the opposite side having the same appearance.

FIGURE 3 is an end elevation as seen from the left-hand side of FIGURE 2.

FIGURE 4 is an end elevation as seen from the right-hand side of FIGURE 2.

The ornamental design for a lawn sprinkler, substantially as shown and described.
